UNITED STATES PATENT OFFICE

ALFRED D. MOSBY, OF CHICAGO, ILLINOIS, ASSIGNOR TO EQUIPMENT CORPORATION OF AMERICA, OF CHICAGO, ILLINOIS, A CORPORATION OF DELAWARE

CONCRETE MIXER

Original application filed February 10, 1927, Serial No. 167,126. Divided and this application filed September 30, 1927. Serial No. 223,116.

The present invention relates to concrete mixers.

The present application is a division of application Serial No. 167,126, filed February 5 10, 1927, by the present applicant.

An object of the present invention is to provide a rigid structure of relatively light weight which can be manufactured at a minimum of cost.

10 A further object is to provide a hitch in combination with the supporting members of a concrete mixer, which hitch may be positioned out of obtrusive relationship with the remainder of said mixer when said mixer is located at a certain definite place and which may be moved to its operative position with a simple movement when it is desired to use said hitch for moving said concrete mixer.

20 A further object is to provide a supporting structure for a concrete mixer which provides the necessary stiffness in members which may be readily shaped up out of relatively light metal.

25 A further object is to provide a concrete mixer having a mixing vessel and motive means for turning said vessel, both mounted upon a readily transportable truck, the parts being so arranged that the necessary stiffness is combined with ease of assembly and disassembly.

30 With these and various other objects in view, the invention may consist of certain novel features of construction and operation, as will be more fully described and particularly pointed out in the specification, drawings and claims appended hereto.

35 In the drawings, which illustrate an embodiment of the device and wherein like reference characters are used to designate like parts—

40 Figure 1 is a view in side elevation of a concrete mixer embodying the principles of the present invention, the hitch above referred to being disposed in unobtrusive relationship with the remainder of said mechanism;

45 Figure 2 is a sectional view taken substantially in the plane as indicated by the line 2—2 of Figure 1;

50 Figure 3 is a sectional view taken substan-

tially in the plane as indicated by the line 3—3 of Figure 1;

55 Figure 3^a is an end elevation taken substantially in the plane of the end wall of the housing shown in Figure 1;

Figure 4 is a view on an enlarged scale taken substantially in the plane as indicated by the line 4—4 of Figure 1;

60 Figure 5 is a fragmentary view on an enlarged scale showing a section taken substantially in the plane as indicated by the arrows 5—5 of Figure 1;

65 Figure 6 is a sectional view on an enlarged scale taken substantially in the same plane as Figure 2, that is—along the plane as indicated by the line 2—2 of Figure 1 but showing the hitch disposed in its operative relationship with the remainder of the mechanism; and

70 Figure 7 is a sectional view taken substantially in the plane as indicated by the line 7—7 of Figure 6.

75 The concrete mixer illustrated is supported by the front leg 10, which, as shown in Figure 2, takes the form of a truncated V, having the front wall 11 and the two side walls 12—12 flaring rearwardly from said front wall 11. Each of the side walls 12 tapers from a region intermediate of its length to the upper and lower extremities of the leg 10. The region of greatest depth of each side wall 12 provides attaching means for a corresponding side brace 13, which side braces may be ordinary commercial channels. Said side braces 13—13 are disposed in flaring 80 relationship with one another, the angle between said braces 13—13 being substantially equal to the angle between the walls 12—12 of the leg 10, whereby said braces 13—13 may be united to said leg by simple means involving only bolts or rivets, indicated by the numerals 14—14. The rear portions of the braces 13—13, which rear portions are indicated by the numerals 15—15, are disposed in parallel relationship with each other and are supported upon the axle 16, brackets 17—17 being provided between said axle and said portions 15—15 of the braces 13—13. The axle 16 carries the wheels 18—18. The diameter of said wheels will 95

90

95

100

preferably be so chosen relative to the leg 10 that the braces 13—13 will be substantially parallel with the surface of the ground. The bottom of the leg 10 may be provided with the foot 19, which may be a simple piece of sheet metal bent into angular form and riveted or otherwise secured to the leg 10.

Riveted or otherwise secured to the portions 15—15 of the side braces 13—13 is the metal plate 20, which is preferably of triangular formation viewed lengthwise of the mixer, as clearly shown in Figure 3. The plate 20 is provided with the side stiffening walls 21—21, the lower extremities of which are arranged in parallel relationship with one another and are spaced apart a sufficient distance to fit closely within the webs of the channel members comprising the side braces 13, being secured to said webs by means of the rivets 22. The stiffening walls 21—21 are arranged in converging relationship with one another and each of said walls preferably tapers from its lower portion to the upper portion thereof. The upper portion of the plate 20 has secured thereto the bearing member 23, which bearing member has secured in cooperative relation therewith the bearing member 24. Said bearing members 23 and 24 enclose the shaft 25, which will be further referred to hereinafter. The upper extremity of the leg 10 is provided with a bearing member 26, which has secured in cooperative relationship therewith the bearing member 27. Said bearing members 26 and 27 are preferably in alignment and enclose the shaft 28, shown in dotted lines in Figure 1. Said shaft 28 and shaft 25 are preferably arranged in alignment with one another. The numeral 29 indicates a cradle or yoke, one end of which comprises the shaft 28 immediately above referred to. The other end of said cradle 29 is apertured to receive the shaft 25 supported by the plate 20, either directly or indirectly. The shaft 25 may simply support the apertured cradle in the bearing of plate 20, or the cradle may be provided with an apertured trunnion supported by the plate 20, and shaft 25 rotatably mounted in said trunnion. Intermediate of the length of the cradle 29 is a pivotal bearing 30 for supporting the mixing vessel 31. Said mixing vessel or drum 31 is provided with the circular rack 32 engaged by the pinion 33, which pinion is secured to the shaft 25. The shaft 25 is driven by any preferred motive means (not shown), which motive means may be supported by the portions 15—15 of the side braces 13—13. The motive means referred to is housed within the casing 34, one end of which casing is illustrated in Figure 3^a. When the shaft 25 is driven by the motive means within the casing 34, power will be communicated through the pinion 33 to the circular rack 32 to rotate the vessel 31 to mix the materials within said vessel 31. When it is required to tilt the

vessel 31, this tilting action may be accomplished by turning the shaft 28. Means for accomplishing the rotation of the shaft 28 and for holding said shaft in any preferred angular position will be referred to presently.

From an inspection of Figure 3^a it will be noted that the end wall 35 of the casing 34 is cut out to provide a substantially triangular aperture 36 defined by the walls 37—37. Said end wall 35 is formed at the upper portion with a continuation of said aperture 36 to clear the shaft 25. The plate 20 is of sufficient size to cover the aperture 36 in the end wall 35 of the casing 34. By reason of the construction illustrated, the casing 34 may be assembled upon the side braces 13—13 or disassembled therefrom without interfering with the shaft 25 or the bearings thereof.

The shaft 28, which controls the tilting of the mixing vessel 31, has secured thereto the internal gear 38 adapted to be driven by the pinion 39, shown in dotted lines in Figure 1 and shown in full lines on a larger scale in Figure 4. Said pinion 39 is driven by the shaft 40 (Figures 4 and 5), which shaft 40 may be driven by the hand wheel 41. Said shaft 40 is supported by the bracket 42, bolted or otherwise secured to the forward face of the leg 10. Said bracket 42 is provided at its outer extremity with the split bearing 43, which bearing is adapted to be contracted by means of the lever 44, which lever is adapted to apply a compressive action to said split bearing 43 through the cooperating cam members 45 and 46. In order to communicate said compressive force to the split bearing 43, said bearing is provided with the two bosses 47 and 48, which bosses are normally separated an appreciable distance by the split 49. Disposed in apertures in said bosses 47 and 48 is the shaft 50, one terminal of which is provided with the head 51 adapted to bear against the bearing head 52, which in turn is adapted to communicate force to the boss 47. The extremity of the shaft 50 opposite from the head 51 is provided with the nut 52^a, which may be screw-threaded or keyed to said shaft 50. It will be clear without detailed explanation that movement of the lever 44 about the axis of the shaft 50 will vary the compressive force of the split bearing 43. When it is desired to hold the shaft 40 and the pinion 39 in any desired position of angular adjustment, it is necessary only to move the lever 44 to grip said shaft 40 against rotative movement. Under these conditions the internal gear 38, shaft 28 and cradle 29 will be securely held against rotation, whereby the axis of the mixing vessel 31 may not be tilted. However, when it is desired to tilt the mixing vessel 31, it is only necessary to move the lever 44 to relieve the gripping action of the split bearing 43 upon the shaft 40, after which the hand wheel 41 may be manipulated to turn the pinion 39, 130

internal gear 38 and cradle 29 to tilt the mixing vessel 31.

The hitch above referred to for holding the concrete mixer is indicated by the number 53. As illustrated, said member 53 comprises a channel member bent intermediate of its length to provide two parallel side walls 54—54 and the bent portion 55. The side walls 54—54 are perforated adjacent to the bent portion 55 for the reception of a hand grip 56, which comprises a simple straight bar. Said hitch 53 extends through perforations 57 in the front wall 11 of the leg 10. In order to provide this perforation, the metal of said front wall may be cut and folded back to form the overlaps 58—58. Said folded back portions 58—58 reinforce the edges, which are subjected to considerable wear from the hitch 53. Supported by the two side braces 13—13 in rear of the leg 10 is the shelf 59, which may be secured to said side braces 13—13 by any preferred means. As shown, the shelf 59 is provided with the downwardly extending flange 60 for stiffening purposes. Disposed symmetrically of the width of the shelf 59 is the catch member 61 which may be riveted or otherwise secured to the shelf 59. Said catch member 61 has at its forward extremity the hooked over portion 62 and at its rear extremity the upwardly disposed end portion 63. Disposed between the two inner extremities of the hitch 53 is the rod 64, which may be riveted to the two side arms 54—54 of said hitch 53. Folded around the rod 64 in a manner to have rotative movement with relation thereto, is the strap 65. The outer swinging extremities of the folded strap or link 65 may be secured together if preferred, or, as shown in Figure 7, may merely depend upon the stiffness of the material to maintain same in position. A finger hold 66 is attached to the outer swinging extremity of said strap or link 65. The folded over portion of the strap 65 has a diametrical dimension such that it may be more or less closely received within the hooked over portion 62 of the catch member 61. When said folded over end portion of the strap 65 is disposed within said hook portion 62 the outer swinging extremity of the strap 65 is disposed forwardly of the upturned flange 63 and adjacent thereto. It will be noted that when the hitch 53 is in operative relationship with the concrete mixer, that is to say—when the rod 64 with the folded over strap 65 is disposed within the hook portion 62, a forward pull on the hitch 53 will be communicated to the concrete mixer through said hook portion 62 of the catch member 61 and through the shelf 59 to the side braces 13—13. If a reverse movement should be given to the hitch 53, the swinging extremities of the strap member 55 will abut against the upturned flange 63, resulting in a toggle action against the upper portion of the hook

portion 62. Such a reverse movement of the hitch 53 will therefore not result in the disengagement of said hitch. It will be observed that when a reverse movement is communicated to the hitch 53 when the strap 65 is disposed between the hook portion 62 and the abutment 63, the parts will have a toggle action, the folded portion 64 of the strap 65 having an upward action against the hook portion 62. When it is desired to move the hitch 53 to an unobtrusive position, the strap may be swung clear of the upturned flange 63, after which the hitch 53 may be slid rearwardly. The hand grip 56 will limit rearward movement of said hitch 53. When in said unobtrusive position the rear extremity of the hitch 53 will rest upon the axle 16.

Though a preferred embodiment of the present invention has been described in detail, many modifications will occur to those skilled in the art. It is intended to cover all such modifications that fall within the scope of the appended claims.

What is claimed is—

1. In combination, a forward leg, a rear axle, said leg comprising a channel member, side braces connecting said forward leg to said axle, a hitch disposed within the web of said channel, a catch member carried by said braces and catch means carried by said hitch, said catch means being adapted to engage with said catch member when a forward pull is exerted upon said hitch, said catch means comprising a pivoted member, said catch member having an abutment portion and a hook adapted to cooperate with said pivot member and said hitch with a toggle action when a reverse movement is communicated to said hitch.
2. In a vehicle, in combination, supporting means, a catch member comprising a hook and a rear abutment, a hitch adapted to have sliding relationship with said support means, said hitch having a member hinged to the rear extremity thereof, said pivot member being adapted to seat itself within said hook whereby pulling force upon said hitch will be communicated to said hook and adapted to have abutting relationship with said rear abutment and with said hook with a toggle action when a reverse movement is communicated to said hitch.
3. In a vehicle, in combination, a front leg, a rear axle, side braces, a catch member supported by said cross braces, said catch member comprising a hook and a rear abutment member, and a hitch slidably disposed within said leg and having a link pivoted to the rear extremity thereof, said link being adapted to lie within said hook and said rear abutment and being adapted to react against said abutment and said hook when a rearwardly directed force is applied along said hitch.
4. In combination, a forward leg, a rear

axle, braces connecting said forward leg to said axle, a hitch comprising an elongated member disposed within an aperture in said forward leg and adapted when in inoperative position to have its rear extremity supported by said rear axle, a link pivotally connected to the rear extremity of said elongated member, and a catch member supported by said braces, said catch member being provided with a hook portion adapted to have hooking engagement with said elongated member, said catch member being provided with a rear abutment portion adapted to cooperate with said hook portion and said link to prevent the accidental disengagement of said elongated member from said catch member.

5. In combination, front supporting means, a hitch adapted to be slidably supported by said front supporting means, means adapted to support the rear extremity of said hitch when said hitch is in inoperative position, a catch member rigidly secured with reference to said front leg, a link carried by said hitch, said catch member having a front hook and a rear abutment adapted to cooperate with said link with a toggle action to prevent accidental disengagement of said hitch from said catch member.

6. In a vehicle, in combination, a front leg and a rear axle, said front leg having a flat front wall, said flat front wall being provided with an aperture, which aperture is provided by swedging the metal of said front wall at the top and bottom of said aperture into lapped relationship with the adjoining portions of said front wall whereby to provide long-wearing bearing surfaces, a hitch slidably disposed within said aperture and adapted to have bearing relationship with said rear axle, and a catch member rigidly mounted with relation to said front leg, said hitch being adapted to have hooking relationship with said catch member.

7. In a vehicle, in combination, a front leg and a rear axle, said front leg having a flat front wall, said flat front wall being provided with an aperture, which aperture is provided by swedging the metal of said front wall at the top and bottom of said aperture into lapped relationship with the adjoining portions of said front wall whereby to provide long-wearing bearing surfaces, a hitch slidably disposed within said aperture and adapted to have bearing relationship with said rear axle, and a catch member rigidly mounted with relation to said front leg, said hitch being adapted to have hooking relationship with said catch member, said hitch being provided with a link at its rear extremity, said catch member being provided with a hook portion and an abutment portion adapted to have a toggle action relative to said link whereby to prevent the accidental disengagement of said hitch from said catch member.

8. In a vehicle, in combination, means for supporting the forward extremity of said vehicle, wheels at the rear of said extremity of said vehicle, a hitch adapted to have sliding relationship with said supporting means and adapted to be supported at a region near the rear extremity of said vehicle, and a catch member having a hook portion and an abutment portion adapted to cooperate with said hitch with a toggle action.

9. In a vehicle, the combination of a supporting frame, supporting members for said frame, said members including a leg, and a wheel and axle assembly spaced from said leg, means for moving said frame, said means being supported directly by said leg and being adapted to be supported in inoperative position on said wheel and axle assembly, and a member carried by said frame normally dissociated from said means and adapted to be engaged by said means when said means is in operative position for movement of said frame.

10. In a vehicle, the combination of a supporting frame, supporting members for said frame, said members including a leg, and a wheel and axle assembly spaced from said leg, means for moving said frame, said means being supported by said leg, and a member carried by said frame independent of said means in inoperative position and adapted to be engaged by said means when said means is in operative position for movement of said frame.

Signed at Chicago, Illinois, this 24th day of September, 1927.
